CLAIM

The ornamental design for a video surveillance post as shown and described.

DESCRIPTION

FIG. 1 is a front, top perspective view showing the new, original, and ornamental design of a video surveillance post in a use of environment;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in the drawings illustrate portions of the video surveillance post and forms no part of the claimed design. The additional broken lines only seen in FIG. 1 are for the purposes of disclosing environment and forms no part of the claimed design.

1 Claim, 5 Drawing Sheets
